I. Carter,

Rotary Pump,

No 11192.

Patented June 27, 1854.

UNITED STATES PATENT OFFICE.

IRA CARTER, OF CHAMPLAIN, NEW YORK.

PUMP.

Specification of Letters Patent No. 11,192, dated June 27, 1854.

To all whom it may concern:

Be it known that I, IRA CARTER, of Champlain, in the county of Clinton and State of New York, have invented a new and Improved Mode of Making Force-Pumps; and I do hereby declare that the following is a full and exact description thereof, reference being had to the accompanying drawings and to the letters of reference marked 10 thereon.

The nature of my invention consists in the peculiar form and operation of some of its constituent parts, with which I construct pumps to be operated two different ways, including, first, the body of the pump composed by two shells so formed that one of them envelops the other, their dimensions and appendages hereinafter described. The outside shell I call a cylinder, the inside shell 15 I call a core, and with the same patterns by changing the locality of the induction valves and some other appendages, I construct pumps to be operated by applying the power to a lever attached to the core, and also 20 to be operated by applying the power to a lever attached to the cylinder. Secondly, the form and operation of the induction valves, and mode of placing them, and, thirdly, the mode of oscillating by a combination of gearing whereby two cranks are brought to act upon one lever between them 25 vertically attached to that part of the pump to be operated.

To enable others skilled in the art to make 30 and use my invention I will proceed to describe its construction and operation.

Commencing with the body of the pump by a core and cylinder affixed horizontal, in 35 all cases when the power is applied to either 40 of these shells the other must be made firm by means hereinafter described to a frame or any other foundation desired. I make a cylinder round at the ends and with flanges to bolt the heads to, and around the whole 45 length $\frac{1}{4}$ of the circumference. The remainder is occupied by a hollow lug raised tapering each side, toward the center till it meets the core-shaft. The core is a tubular shaft through the center of the cylinder. 50 Its ends work as journals in the cylinder heads. It has a lug upon it that fills $\frac{1}{4}$ part of the whole cylinder, thus inclosing a vacant space in each side between the lug belonging to the core, and the lug belonging to the cylinder. I make a groove in the lug 55 belonging to the cylinder for packing against

the core shaft, and I make another groove directly above that in the shell of the cylinder and continue it down at the ends in the cylinder heads to meet the former groove, by 60 a recess around the core journals, for packing also, thus stopping all leakage by a belt of packing longitudinally around the lug of the core. Said lug is hollow. Its inside 65 serves as an air chamber, and its outside acts in the capacity of plungers.

I in general construct my pump principally of cast-iron. The cylinder requires no finishing with the exception of a few bolt holes and bushing the cylinder heads for the core 70 journals to work in. All the round part of the core should be turned and made smooth that the packing may slide easily upon it. I prefer leather packing for cold water. Where heat meets it soft metal may be used 75 or cotton. The red where it is found in the accompanying drawings shows the grooves containing the packing.

The Figures I, II, III, and IV show the mode where the cylinder is made stationary 80 and the pump operated by applying the power to a lever attached to the core. Figs. V and VI show the mode where the core is made stationary and the power applied to the cylinder. Fig. I is an external perspective view of the end where the cranks are applied to the lever, Fig. II is an external section of the other end showing the gears to operate the cranks, Figs. III and V are longitudinal sections of the two modes of 85 operating showing the body of the pump split through the middle, Figs. IV and VI are transverse vertical sections of the two modes of operating also.

The same letters refer to like parts in both 90 cases.

A A are the cylinder heads.

B B are friction wheels on the wrists of the cranks C C, which operate on lever D, said lever being made firm on the end of 100 the core shaft E.

F F are bevel gears on the ends of the crank shafts H H.

G G are boxes attached to the cylinder heads extended out like arms for the crank shafts to run in. The cranks are made firm on the shafts at one end of the pump and the gears at the other end. The motion I require to drive my cranks I accomplish by connecting their shafts with two pairs of bevel gears, or one pair of spur gears, which drives them contrary ways, their revolutions 105 110

being so divided that one of the cranks carries the lever over till it meets the other friction wheel and crank, which returns it, thereby sweeping $\frac{1}{3}$ part of the circle in the cylinder. The advantage I gain in this mode of oscillating is the applying the starting power on the longest purchase, and obtain more sweep than is practicable to obtain by a single crank.

10 I in the other figures refer to the induction pipe.

J J are two driving pinions upon shaft K. To this shaft may be attached two cranks and operated by men or by a belt and 15 pulley.

L is a box attached to the cylinder head for driving shaft K to run in.

M refers to the eduction pipe.

n n n refers to the cylinder.

20 o o o refers to the core.

I will now proceed to conclude the description: Where the cylinder is made stationary, I make the cylinder round at the ends, with flanges to bolt the heads to. I 25 make both heads of one pattern with feet R R by which the pump is bolted to whatever the case may require. I make a square opening in the shell under the lug S belonging to the cylinder, where I insert the induction valves being housed in by said lug. I make the valves hollow to do away with 30 heft, and make them in the following form:

The side that closes the port holes I make on a curve and tapering to a small round 35 in the angle 42° and flat surfaces on the ends. I hinge the said valves to a bar between them, in the circle of the main shell of the cylinder and being housed in the lug belonging to the cylinder. Thereby said valves

40 p p inclose an air chamber T, between them, it being an advantage to their operation. Another advantage in the principle of these valves is their closing the port holes on a circle section against the water after it 45 passes them, thereby obviate the backlash and lost suction which all pumps are subject to. Said valves follow each other in their motion and open and shut as the core oscillates above them. The port holes are oblong

50 square like mortises in each side of the lug next to the main shell of the cylinder. I make the shell around the opening under the valves to sag down in order to give it the right shape to bolt the induction pipe to it. The core o o o, is a tubular shaft

55 through the center of the cylinder and has a lug upon it that fills about $\frac{1}{3}$ part of the cylinder, leaving a vacant space in each side to receive the water, which is from thence

admitted into the core by a pair of valves 60 q q and discharges out of one end of the core shaft into the eduction pipe M, that meets it in the cylinder head. The other end of this core shaft is closed up and extends out through the cylinder head, and has a lever 65 attached to it by which this pump is operated. The other mode of operating where the core, is made stationary as shown by Figs. V and VI, I make the cylinder precisely the same shape of the former inside 70 with a lug S raised toward the center, but no port holes in it. All the valves are applied to the core in this case. I make a partition in the middle of the core and divide the tube into two disconnected parts 75 and apply a pair of valves to each part. One pair p p allows the water to pass into the cylinder, and another pair q q admits it into the other part of the core and discharges as in the other mode of operating, 80 making one end of the core shaft the induction pipe I and the other end of core shaft the eduction pipe M. I let both ends of the core shaft extend out through the cylinder heads in this case, and put a collar 85 on each of them secured by set screws or keys. Said collars branch downward like legs r r, which may be bolted to a frame or platform, thereby make the core stationary. This pump can be operated by a lever 90 attached to any part of the cylinder.

What I claim as my invention and desire to secure by Letters Patent is—

1. The mode of attaching the lug herein described made to the cylinder, and the 95 grooves to contain the packing.

2. The form and operation of the induction valves being housed in by the lug of the cylinder inclosing an air chamber between them, and closing the port holes on a circle section against the water after it passes them, thereby obviating lost suction.

3. The form and principle of the core which may be made a stationary part in a pump, or an operative part by changing the 105 locality of the induction valves only.

4. And fourthly the mode of oscillating by two cranks with friction wheels on their wrists being brought to act upon one lever between them, vertically attached to that 110 part of the pump to be operated, said cranks being made firm on two parallel horizontal shafts, geared to revolve equal speed and gathering at the top.

IRA CARTER.
